UNITED STATES PATENT OFFICE.

HENRY L. SCHOLL, OF SPOKANE, WASHINGTON.

WINDOW-SASH HOLDER.

1,423,034.

Specification of Letters Patent.

Patented July 18, 1922.

Application filed December 20, 1919, Serial No. 346,222. Renewed April 11, 1922. Serial No. 551,469.

To all whom it may concern:

Be it known that I, HENRY L. SCHOLL, a citizen of the United States, residing at Spokane, in Spokane County and State 5 of Washington, have invented certain new and useful Improvements in Window-Sash Holders, of which the following is a specification.

My present invention relates to a new and 10 improved window-sash holder of the swinging bolt variety, and designed to be attached to one sash, as the lower one, and impinge against or contact with a portion of the upper sash, to hold either or both sashes in 15 adjusted position. The primary object of the invention is the provision of a device for this purpose that is comparatively inexpensive in cost of production, simple in construction and operation, durable, and 20 thoroughly efficient in performing its intended function of holding the sashes in desired relative position. To this end the invention consists essentially in a supporting bracket attached preferably to the upper 25 portion of the lower sash and provided with a novel form of swinging bolt to be wedged or cammed in close frictional contact with the upper sash, thus providing means for holding the lower normally positioned sash in rigid relation with the adjusted upper sash, or permitting an elevation and retention of the lower sash with relation to the upper sash, and also enabling the upper sash to be lowered and the lower sash to 30 be lifted and held in rigid relation one with another.

In the accompanying drawings I have 35 illustrated one complete example of the physical embodiment of my invention constructed and arranged according to the best mode I have so far devised for the practical application of the principles of my invention.

Figure 1 is a perspective view showing so 40 much of the window frame and the upper and lower sashes, as is necessary for a clear understanding of the exemplification of my invention.

Figure 2 is an enlarged perspective view 45 of the device on the upper cross bar of a lower sash and engaging the side bar of an upper sash.

Figure 3 is a side elevation of the retaining device or holder, detached.

50 For the purpose of illustrating the application and use of my novel holding device

I have indicated the conventionalized form of window frame 1, with the upper sash 2 and the lower sash 3 of usual form and including the upper transverse bar 4 of the lower sash and vertical side bar 5 of the upper sash, with which members the device of the invention co-acts, and said device is indicated as a whole by the numeral 6 in Figure 1 and secured on the top of the upper transverse bar 4 referred to.

The supporting bracket is preferably made of strong sheet metal as brass or steel with the two sides 7, 7, and angular flanges or base plates 8, 8, which, by means of the screws 9, are attached to the transverse bar 4 as shown in Figure 2. The bracket may also be of cast metal if desired, but in any event is made of the general outline and shape indicated, with a front, inclined or angular wall 10 joining the two side walls 7, and fashioned with a pair of slots 11, 11 spaced away from the front wall 10, and lying in a plane approximately at right angles to the inclined plane of the front wall 80 or plate 10. Within the oppositely disposed, complementary slots 11, 11 is journaled a swinging bolt 12 in the form of a U shaped bail, and on the inwardly bent ends of the bail a roller 12 is journaled which may be 85 swung outwardly to inoperative position as in Figure 3, or inwardly to operative position as in Figure 2, which figures clearly show the action of the swinging bolt.

In Figure 2 it is apparent that the roller 90 is jammed between the inclined face or plate 10 of the bracket and the face of the side bar 5 of the upper sash, and that power applied to the upper sash to lower it, or power applied to the lower sash to raise it, will 95 only result in clamping the roller tighter between the two adjoining faces with the result that the two sashes are more intimately locked together. However, it will be clear that the upper sash may with facility 100 be raised to close the upper sash of the window, as it is evident that lifting this sash will disengage the roller from the surfaces between which it is jammed. Thus, after the window sashes are once adjusted 105 the upper, lowered, one cannot be further lowered or opened from the outside, nor can the lower, raised sash be lifted from the outside, for the reason that they are locked on the inside by the holder which is inaccessible, and unauthorized ingress is prevented.

The slots provide for free movement of the bail or swinging bolt, and permit the roller to adapt itself to irregularities on the surface of the upper sash bar, and if desired the roller may be corrugated as shown to insure a close frictional contact with the friction surfaces 10 and 5. Usually one of the holders will be sufficient to retain the window sashes in adjusted position, but of course one may be used at each side of the sash if desired to insure stability and firmness in the holders.

Having thus fully described my invention, what I claim and desire to secure by Letters Patent is—

A window sash holder consisting of an

integral bracket having an attaching base plate, an inclined front plate, vertical side walls and rearwardly declining straight slots in said walls lying in a plane approximately perpendicular to the front plate, a U-shape bail journaled in the walls, a roller journaled on the bail to co-act with the front plate, and said bail adapted to form a pivot and the upper ends of the slots located in position, whereby the roller may be swung over the top of the bracket and rest on the rear edges of the walls of the bracket.

In testimony whereof I affix my signature.

HENRY L. SCHOLL.
